UNITED STATES PATENT OFFICE.

BERT ARTHUR LINDERMAN, OF CHICAGO, ILLINOIS.

CABINET FOR DOMESTIC LIGHTING PLANTS.

1,396,223.

Specification of Letters Patent.

Patented Nov. 8, 1921.

Application filed May 19, 1920. Serial No. 382,515.

To all whom it may concern:

Be it known that I, BERT ARTHUR LINDERMAN, a citizen of the United States, residing at Chicago, in the county of Cook and State 5 of Illinois, have invented certain new and useful Improvements in Cabinets for Domestic Lighting Plants, of which the following is a specification, reference being had therein to the accompanying drawing.

10 This invention relates to domestic lighting plants and in particular to cabinets for inclosing such electrical apparatus.

The object of our invention is to inclose a domestic lighting plant in a cabinet so that 15 not only the dust, dirt and accumulations of material will not collect upon this electrical apparatus and internal combustion engine, but also to the end that persons who are not authorized may not tamper with the apparatus.

20 There is an additional object in putting an electrical power plant in a cabinet. That object is to inclose in one receptacle all of the control apparatus of the power plant and 25 to seal it in a box. This successfully accomplishes the end of preventing the owner of the apparatus from tampering, or having tampered with, the delicate electrical mechanism constituting the control apparatus. 30 This has been found to be the greatest source of annoyance and trouble. It is largely due to the fact that persons unskilled in electrical work have endeavored to adjust the control contacts. By this method, when a part of 35 the control apparatus goes wrong, the box in its entirety can be withdrawn and returned to the manufacturer with the seal on its cover unbroken.

40 My invention comprehends the use of such a case or box which may be pushed into the cabinet so that its outer face will be flush with that of the cabinet, only leaving displayed the several push buttons for the operation of the power plant or other apparatus 45 as may be necessary for the particular operation of the particular plant.

A cabinet of this character may be accessible on its sides for adjustment of the engine and mechanical parts of the mechanism.

50 It also must permit of placing the proper oil and water in the engine, in case the power plant is a water cooled apparatus.

Referring to the several figures on the ac-

companying drawings which illustrate my invention—

55

Figure 1 is a side elevation of a cabinet embodying my invention, showing the side doors of the cabinet, means of connection of the doors to the cabinet, means of locking the doors and means of joining the various parts 60 of the cabinet together;

Fig. 2 is a plan view of the top of the cabinet showing in dotted lines the box inserted in the cabinet at one end carrying the control apparatus and showing in dotted lines 65 at the other end the radiator and radiator vent; and

Fig. 3 is a front elevation showing the location of the control box as installed in the cabinet.

70

Referring to Fig. 1, 1 is a base, 2 is a side door and 3 is another side door co-operating with the door 2. By the edge 4 of the door 3 overlapping the door 2 and the lock generally designated at 5, the two doors can 75 be locked together and locked shut on the cabinet frame. The doors are hinged at 6—6 to the cabinet frame 7. The end post arrangement 8 may be integral with the end plates of the cabinet or separate therefrom. 80 9 is the detachable box for the control apparatus, shown in dotted lines installed in the cabinet. 10 is the locking screw which holds the control box in place. 11 is the end plate of the front of the cabinet. 12 is 85 the top plate fastened to the end plates by the connecting means 13. 14 is the radiator cap and 15 is the radiator vent in the top of the cabinet 12. 16 is the radiator shown in dotted lines. 17 is a removable plate 90 which may be taken out when the radiator is installed or removed. The radiator is held in place by the setting and retaining means 18.

When it is desired to open the cabinet the 95 lock 5 is actuated through the handle 19 and the doors 2 and 3 are swung open, giving full access to the interior of the mechanism. When it is desired to put water into the radiator the radiator cap 14 can be unscrewed and the water placed in the radiator 16.

When it is desired to remove the control apparatus in its box 9 the set screws 10 are loosened and the entire box with its apparatus is removed. When it is desired to

105

take off the top of the cabinet the retaining screws 13 can be taken out and the top readily lifted off. The plate over the radiator can be suitably perforated to allow air 5 to be drawn through which can pass out around the generator support and housing seen in Fig. 3 below the control box 9.

From the foregoing I believe that the construction of my improved cabinet may be 10 readily understood by those skilled in the art and I am aware that various changes and modifications may be made in the construction illustrated without departing from the spirit of the invention as expressed in 15 the following claims.

Having thus fully described my invention, what I claim as new and desire to secure by Letters Patent, is:

1. A cabinet for domestic lighting plants 20 comprising a base, end frames secured thereto, a top having a hole therein, side doors, a radiator secured to the interior of the end

frames and having a cap projecting through the hole in the top, a control box also attached to the interior of the frame and a 25 lock for the doors.

2. A cabinet for housing a domestic power plant including a base, a top, an end plate connecting the base and a top and having an opening therein, a detachable control box arranged in said opening and projecting into the interior of the cabinet, a second end plate carrying a radiator which is arranged within the cabinet, a cap for the radiator extending to the exterior of the cabinet to 35 permit filling of the radiator without opening the cabinet, one side of the cabinet being provided with an opening, doors normally closing said last mentioned opening, a latch for locking said doors in closed position, 40 and means for locking the control box in position.

In testimony whereof, I affix my signature.
BERT ARTHUR LINDERMAN.
